METHOD OF REFINING HYDROCARBON OILS

Arthur Lachman, Berkeley, Calif., assignor, by
mesne assignments, to Vapor Treating Pro-
cesses Inc., a corporation of California

Application June 27, 1930, Serial No. 464,350
Renewed February 6, 1936

22 Claims. (Cl. 196—42)

This invention relates to an improved method of refining hydrocarbon oils, and more specifically refers to the treatment of naphtha or gasoline stocks produced by cracking petroleum oils, shale 5 oils or distillates derived from relatively high sulphur bearing crude oil in which hydrogen sulphide, mercaptans and other sulphur bearing hydrocarbons as well as varying percentages of 10 unstable hydrocarbons, such as diolefines and acetylenes may be present or formed during said cracking or distillation operation. This application is a continuation in part of my pending application Serial No. 361,513 filed May 8, 1929 for 15 Process of refining hydrocarbon oils.

15 The process of refining hydrocarbon oils, as described in this application, is applicable to all mineral oil products derived by distillation or by any cracking operation of crude petroleum oil, fuel oil, shale oil and distillates of the same.

20 Gasoline or naphtha stocks obtained by distillation of crude petroleum oil or by cracking higher boiling petroleum oil distillates or fuel oil, comprises a mixture of saturated hydrocarbons, 25 stable unsaturated and unstable unsaturated hydrocarbons, together with sulphur compounds, nitrogen bases and other substances of an undefined nature. These latter substances, such as the unstable unsaturated hydrocarbons and sulphur compounds, are readily oxidizable at ordinary 30 temperature and are usually responsible for the change of color which may take place when refined gasoline is stored that has not been refined to the required degree. These oxidizable substances are removed with difficulty by the 35 methods now in common use.

By well-known methods gasoline or naphtha stock obtained from cracking higher boiling petroleum oils or gasoline stock obtained by the distillation of relatively high sulphur bearing 40 crude oils are usually purified by treatment with sulphuric acid which may range from $\frac{1}{2}$ of 1 per cent or lower to as high as 8 per cent by weight sulphuric acid, the quantity of acid depending upon the nature of the gasoline stock 45 to be treated and the product desired. This acid treatment usually consists in commingling the gasoline stock with the required amount of sulphuric acid necessary to obtain the desired extraction, either by the well-known batch or continuous treating method, after which the excess acid and products of reaction are separated from the treated gasoline stock. The acid treated gasoline stock is then neutralized by washing with a water solution of an alkali and finally 55 with water. This treatment removes most of the

impurities but subsequent treatments are usually necessary to deodorize and remove or convert corrosive sulphur compounds into non-corrosive bodies. For this purpose, a water solution of sodium plumbite, sodium hypochlorite or other oxidizing agent may be employed to render the gasoline "sweet" to the "doctor test". In these treatments, particularly where hypochlorite of soda is employed, chlorinated hydrocarbons may be formed to a small extent, which may be converted into corrosive compounds during a subsequent heating or distillation. Also, all sulphur remaining in the gasoline after the purification operation form corrosive acid compounds during combustion and if in appreciable amounts, 15 may attack the metal parts of an engine. It is therefore advantageous in the purification of gasoline stock to remove as much sulphur as possible in the treating and sweetening operation.

The general objections to treatments of this character are (1) that gasoline purified by this 20 method frequently becomes discolored when stored for a period of time; (2) considerable quantities of sulphuric acid are required which are expensive to recover; (3) a high percentage of stable unsaturated hydrocarbons contained in 25 the gasoline stock is lost, which may be as much as 10 per cent by volume.

In my pending application Serial No. 361,513 filed May 8, 1929 for Process of refining hydrocarbon oils, it has been disclosed that the sulphuric acid which is normally used to treat crude gasoline stock may be reduced to a high extent and in many cases may be entirely eliminated by passing gasoline vapors coming from a cracking or distillation system at the vaporizing temperature through and in contact with a water solution of certain metallic salts, such as the chloride, bromide, sulphate or nitrate of the metals, zinc, copper, cadmium, mercury, iron, 30 chromium, manganese, aluminum or nickel, and also any of the water soluble salts of the above named metals of organic acids, such as the sulphonate acids of benzol, toluol and xylol, or the sulphonic acids derived from the treatment of 35 petroleum oils with sulphuric acid.

Now, I have discovered an improvement there- 40 to in which I have determined that it is an ad- 45 vantage to mix air with the hot gasoline vapors before they are contacted with the treating so- 50 lution, or during the time the gasoline vapors are being contacted with the treating solution to produce an oxidizing reaction therein suf- 55 ficient to oxidize the corrosive sulphur com- pounds into compounds that may be extracted to

a high extent with the metal salt solution employed. Also which may assist in the polymerization of the unstable, unsaturated hydrocarbons and thereby produce a gasoline stock which is low in sulphur content, "sweet" to the "doctor test" and contains substantially no gums or gum forming constituents.

The hydrocarbon oil stock to be treated by my invention may or may not have had a preliminary treatment with sulphuric acid or other agents to partly purify the same, or may be first partly purified by my invention and the purification completed by methods known in the art, such as treatment with caustic alkali, sulphuric acid, etc. In case of gasoline stocks produced by cracking high sulphur bearing crude petroleum oil or residuum, it may be advantageous to treat such gasoline stocks with small amounts of sulphuric acid before the treatment with a water solution of any of the aforesaid metal salts or mixtures thereof, which may also be followed by treatment with an alkali water solution of sodium, potassium, or calcium hydroxide, or the carbonates of sodium or potassium.

Although a solution of less concentration may be employed which may range from 50 or less to approximately 85 per cent, the strength of the water solution of the metallic salt or mixtures of salts employed is preferably a substantially concentrated solution and the temperature employed for the treatment is approximately 300 to 400 degrees F., which normally fluctuates, depending upon the vaporizing temperature of the oil under treatment.

One of the principal objects of this invention is to accomplish a desulphurization and purification of gasoline stock by a vapor phase treatment with a water solution of a metallic salt or salts at the reacting temperature in the presence of air.

Another object of the invention is to provide a rapid and economical process for purifying gasoline stock produced by the thermo molecular decomposition of higher boiling petroleum oils by treating the same with an agent capable of polymerizing all of the unstable hydrocarbons contained therein and at the same time remove all the corrosive sulphur compounds and render the gasoline "sweet" to the "doctor test".

Another object of the invention is to provide an economical method for improving the color, removing sulphur compounds, gums and gum forming material from gasoline or naphtha stocks, so that the same may be kept in storage for relatively long periods of time without change in quality by the formation of polymerized bodies.

Other objects and advantages will be apparent from the preferred embodiment of this invention which will now be more fully explained by reference to the accompanying drawing, which is a diagrammatical representation of an apparatus in which the invention may be carried out.

Referring to the drawing, 16 indicates a pipe leading to a source of crude gasoline vapors coming from a vaporizing chamber or fractionating tower not shown. Pipe 16 is connected to jet mixer 14, the flow of crude gasoline vapors being controlled by operating valve 17. Pipe 15 controlled by valve 18 leads to an air supply not shown. The quantity of air introduced into the jet mixer 14 ranges from approximately 4 cubic feet to as much as 12 cubic feet or more, per barrel of liquid gasoline supplied calculated at 75 60 degrees F. and 760 mm. pressure, the quantity of air employed depending upon the extent of oxidation required to obtain a sweet gasoline substantially free from sulphur, gums and gum forming constituents. The air supply may also be measured as a percentage of the volume of vapors 5 being treated. The volume of added air normally varies from 0.5 to 1.5 per cent, measured at the same temperature and pressure as the vapors. Pipe 2 connects the jet mixer 14 to treating tower B at the point 9 below the contact 10 material 3. Pipe 8 controlled by valve 21 leads to a supply of water or steam not shown. Pipe 13 controlled by the valve 20 is connected to pipe 8 and leads to a source of air supply not shown, by means of which air may be introduced into treating tower B along with water or steam instead of through the pipe 15. B indicates in general a tower of suitable height and diameter filled with resistant or contact material such as fire brick, spiral tile, rock or the like, 20 indicated by the numeral 3, which forms tortuous passages through the tower, although it is to be understood that the well-known bubble cap contact tower may be employed. Disposed above the tower or adjacent to the same, is a tank 12 25 containing a water solution of a metallic salt or mixtures of the same, as heretofore enumerated, having a concentration of from 50 per cent or less to as high as approximately 85%. Preferably a substantially concentrated water solution of zinc chloride containing an oxide or hydroxide is employed, although a solution of less concentration may be used, the concentration depending upon the stock under treatment and the product desired. Tank 12 is connected to 30 the top of the tower B by means of a pipe 4, having a regulating valve 5. The pipe 4 terminates over a spreader plate 6 and this plate evenly distributes the water solution of the metallic salt or salts, when the valve 5 is open, over the brick 40 work or contact material. The water solution of the metallic salt or salts flows downward through this contact material and may finally be discharged through the bottom by a pipe 7, controlled by valve 19, to a storage not shown 45 and may be thereafter recovered for reuse. As heretofore stated, tower B is provided with a steam or water inlet pipe 8, which may intermittently or continuously supply a predetermined amount of water or steam to the tower B. The 50 hot gasoline vapors coming through the pipe 16 enters the mixer 14 wherein they are continuously mixed with the required amount of air coming through the pipe 15 regulated by valve 18. The quantity of air introduced may range from 55 approximately 4 to 12 cubic feet or more per barrel of gasoline stock to be treated. From the mixer 14 the gasoline vapors commingled with the required amount of air passes through pipe 2 and enters the lower section of the tower B 60 at a point 9. The gasoline vapors commingled with the introduced air pass up through the numerous tortuous passages in the brick-work and thereby come into intimate contact with the said water solution of metallic salt or salts flowing over the contact material 3. Although other temperatures may be employed, the water solution of metallic salt or salts, gasoline vapors and air are generally maintained at a temperature of approximately 300 to 400 degrees F. The purified gasoline vapors and air after passing through the tower B are discharged at the upper end of the tower B through a pipe 10 which is connected with a condenser 11 of suitable construction. From condenser 11 the condensed purified gaso- 75

line and aeriform products pass through pipe 23 to a storage tank not shown where the aeriform products are separated from the condensed gasoline and the retained gasoline separated from 5 the aeriform products by an absorbing system. The gasoline vapors passing through the contact tower B at the temperature specified vaporize a certain amount of water from the water solution of the metallic salt or salts and the purpose 10 of the steam or water inlet 8 is that of maintaining the solution at approximately a certain water content so as to maintain the necessary fluidity which is essential to good contact between the rising gasoline vapors commingled with 15 air and the down-flowing water solution of metallic salt or salts and products of reaction. Preferably the concentration of the water solution of metallic salt or salts is maintained near its predetermined limits of concentration by an 20 intermittent or continuous introduction of water vapor. Otherwise, solid metallic salt or salts and solid reaction products may plug the passages through which the gasoline vapors are being conducted and treated. However, a water solution 25 of the metallic salt or salts of a less concentration may be employed for a period of time without the introduction of water or the contact tower B may be maintained under sufficient pressure to prevent to a great extent loss of the 30 water vapor which maintains the salt or salts in solution.

While not always necessary, it is beneficial that the water solution or metallic salt or salts contain hydroxides or oxides of any of the metals or mixtures thereof heretofore enumerated before being introduced into the system. This may be accomplished by agitating the water solution of the metallic salt or salts with any of the hydroxides or oxides of any of the enumerated 40 metals in a finely comminuted state. The optimum amount of the comminuted metal oxide and/or hydroxide ranges from approximately $\frac{1}{2}$ of 1 per cent to 3 per cent by weight of the water solution of metal salt or salts. When the 45 oxides or hydroxides of any of the aforementioned metals or mixtures thereof are soluble in substantial amounts in the salt or salts solution at the temperatures and pressures employed, the beneficial action will be enhanced, but even 50 if no substantial solubility exists, useful effects will be obtained if the oxides and hydroxides are suspended in the salt or salts solution.

The reaction tower B is preferably kept full 55 of the water solution of the metallic salt or salts, such as zinc chloride, which may contain metallic hydroxides or oxides of the enumerated metals, such as zinc oxide or hydroxide, and a fresh supply of approximately 15 pounds of the 60 said solution is admitted for each barrel of gasoline stock under treatment and a corresponding amount of the spent solution is withdrawn at the same time. The amount of water vapor required to replace the vaporized water from the 65 water solution of metallic salt or salts varies within wide limits, depending upon the concentration of the solution employed, the temperature at which the operation is carried out, the nature and amount of the inert gases which 70 may accompany the gasoline vapors being treated and the air employed for the oxidizing reaction. Approximately 50 to 100 pounds of water or water vapor will usually be sufficient for each barrel of gasoline stock treated, although it is to be understood that the operation 75 may be conducted without the introduction

of water when a larger amount of a solution of less concentration is employed. By this treatment the major portion of the impurities contained by the gasoline vapor is removed and carried out with the water solution of metallic salt or salts as a sludge and the purified gasoline vapors when condensed and separated from the aeriform products, are "sweet" to the "doctor test" and suitable for use as refined gasoline stock of high purity with a low sulphur con- 10

While the process herein described is well adapted for carrying out the objects of the present invention, it is to be understood that various modifications and changes may be made without departing from the invention, such for example, as the use of centrifugal or other like mechanical mixers which do not require the addition of water to maintain a substantial concentrated solution, or the employment of any of the well-known contact towers wherein a water solution of a metal salt or mixtures of metallic salts, either organic or inorganic, heretofore enumerated, may be commingled with or brought into contact with petroleum oil vapor containing air at the reaction temperature, it being observed that the enumerated metals may be classed as heavy metals, and it being understood further that the word "heavy" as used in the term "water soluble salt of a heavy metal" (which latter phrase is embodied in the claims to comprehend the materials capable of use in my process) is to be understood as including those metals which form water soluble salt solutions capable of being maintained in solution at the temperatures and pressures at which the hereinbefore-described process may be practiced, and the invention includes all such modifications and changes as come within the scope of the appended claims.

What I claim is:

1. A process of refining mineral oils, comprising, vaporizing a mineral oil, commingling the vaporized mineral oil with air, contacting the vaporized mineral oil containing the air with a maintained water solution of zinc salt other than zinc iodide, condensing purified mineral oil vapor, and then separating the condensed purified mineral oil vapor from aeriform products.

2. A process of purifying petroleum oil products, comprising, vaporizing and commingling a petroleum oil product with air and a maintained substantially concentrated water solution of zinc salt other than zinc iodide, separating products of reaction, excess treating solution from a purified petroleum oil vapor and aeriform products, condensing the purified petroleum oil vapor and finally separating the condensed purified petroleum oil from the aeriform products.

3. A process of refining mineral oils, comprising, vaporizing a mineral oil by the application of heat, commingling the vaporized mineral oil with air and contacting the heated vaporized mineral oil and the air with a maintained substantially concentrated water solution of zinc salt other than zinc iodide, separating, condensing and collecting a purified mineral oil from products of reaction, treating solution and aeriform products.

4. A process of refining mineral oils, comprising, commingling vaporized mineral oil with air, contacting the vaporized mineral oil containing the air with a maintained water solution of a mixture of zinc salts other than zinc iodide and then separating, condensing and collecting a pu- 75

4. Refined mineral oil from products of reaction, treating solution and aeriform products.
5. A process of refining mineral oils, comprising, vaporizing a mineral oil by the application of heat, contacting the heated vaporized mineral oil with a maintained heated water solution of a zinc salt other than zinc iodide and air and then separating, condensing and collecting a purified mineral oil from products of reaction, treating solution and aeriform products.
10. 6. A process of refining mineral oils, comprising, vaporizing a mineral oil by the application of heat, commingling the vaporized oil with a maintained water solution of a zinc salt other than zinc iodide in the presence of air, heated to a temperature of not less than the vaporizing temperature of the vaporized mineral oil under treatment, and then separating, condensing, and collecting a purified mineral oil from products of reaction, treating solution and aeriform products.
15. 7. A process of refining mineral oils, comprising, heating a mineral oil to form a vapor at a temperature of approximately 300 to 400 degrees F., contacting the heated vapor with a maintained water solution of zinc salts other than zinc iodide and air maintained at a substantially similar temperature, then condensing and collecting a purified mineral oil, separated from products of reaction, treating solution and aeriform products.
20. 8. A process of refining mineral oils, comprising, commingling a mineral oil vapor at temperatures of approximately 300 to 400 degrees F., with air and a maintained water solution of zinc salt other than zinc iodide maintained at a substantially similar temperature, the water solution of zinc salt having a concentration of approximately 50-85%, then condensing and collecting a purified mineral oil, separated from products of reaction, treating solution, and aeriform fluids.
25. 9. A process of refining mineral oils, comprising, heating, a mineral oil to form a vapor, contacting the heated vapor commingled with air, with a maintained water solution of zinc salt other than zinc iodide containing zinc hydroxide and then separating, condensing and collecting a purified mineral oil from products of reaction, treating solution and aeriform fluids.
30. 10. A process of refining mineral oils, comprising, heating a mineral oil to form a vapor, passing the heated vapor commingled with air through and in contact with a maintained water solution of zinc salts other than zinc iodide containing from $\frac{1}{2}$ of 1 per cent to 3 per cent by weight of zinc hydroxide and zinc oxide and then separating, condensing and collecting a purified mineral oil, from products of reaction, treating solution and aeriform fluids.
35. 11. A process of refining mineral oils, comprising, heating a mineral oil to form a vapor, passing the heated vapor commingled with air through and in contact with a maintained water solution of zinc salt other than zinc iodide containing from $\frac{1}{2}$ of 1 per cent to 3 per cent by weight zinc hydroxide and zinc oxide and then separating, condensing and collecting a purified mineral oil from products of reaction, treating solution and aeriform fluids.
40. 12. A process of refining mineral oils, comprising, heating a mineral oil to form a vapor, passing the heated vapor commingled with heated air through and in contact with a water solution of zinc salts other than zinc iodide, maintaining the solution in a fluid condition by the addition of water, condensing and collecting a purified vapor of the mineral oil after passing through the solution.
45. 13. A process of refining mineral oils, comprising, commingling the vapors of a mineral oil containing air with a maintained water solution of zinc salt other than zinc iodide and then condensing and separating treated mineral oil vapors from aeriform products.
50. 14. A process of refining mineral oils, comprising, heating a mineral oil to form a vapor, passing the heated vapor containing air through and in contact with a water solution of zinc salt other than zinc iodide containing zinc hydroxide, maintaining the solution in a fluid condition by the addition of water during contact of the vapors and air with the treating solution and condensing the vapor after passing through the solution.
55. 15. A process of refining mineral oils, comprising, heating a mineral oil to form a vapor, passing the heated vapor commingled with air through and in contact with a water solution of zinc salts other than zinc iodide containing from $\frac{1}{2}$ of 1 per cent to 3 per cent by weight of zinc hydroxide and zinc oxide, maintaining the solution in a fluid condition by addition of water during contact of the vapors and air with the treating solution and condensing the vapor after passing through the solution.
60. 16. A process of refining mineral oils, comprising, heating a mineral oil to form a vapor, passing the heated vapor commingled with air through and in contact with a water solution of zinc salts other than zinc iodide, maintaining the concentration of the solution within predetermined limits by the addition of water, condensing and collecting the refined mineral oil vapors after passing through the solution.
65. 17. A process of refining mineral oils, comprising, heating a mineral oil to form a vapor at a temperature of approximately 300 to 400 degrees F., passing the heated vapor commingled with air through and in contact with a water solution of zinc salts other than zinc iodide, maintaining at a similar temperature and having a concentration of approximately 50-85%, maintaining the concentration of the solution as specified, by the continuous addition of water and then condensing the refined mineral oil vapors after passing through the solution.
70. 18. A process of refining mineral oils, comprising, vaporizing a mineral oil, contacting the vaporized mineral oil commingled with air with a water solution of zinc salt other than zinc iodide, intermittently introducing water into the solution of zinc salt to maintain the salt in solution and continuously condensing and collecting purified mineral oil vapors separated from the products of reaction, aeriform fluids and solution of zinc salt.
75. 19. A process of refining mineral oils, comprising, heating a mineral oil to form a vapor, passing the vapor commingled with air through and in contact with a water solution of zinc salts other than zinc iodide containing zinc hydroxide, intermittently introducing water into the solution of zinc salts containing zinc hydroxide to maintain the salts in solution and continuously condensing and collecting purified mineral oil vapors separated from the products of reaction, solution of zinc salts and aeriform fluids.
80. 20. A process of refining mineral oils, comprising heating a mineral oil to form a vapor, passing the vapor commingled with air through and in contact with a water solution of zinc salt

other than zinc iodide containing zinc oxide, intermittently introducing water into the solution of zinc salt containing zinc oxide to maintain the salt in solution and continuously condensing vapors of purified mineral oil separated from the treating solution, products of the reaction and aeriform products.

21. A process of refining mineral oils comprising commingling the vapors of a mineral oil containing air with a maintained water solution of a heavy metal salt other than an iodide,

and then condensing and separating the mineral oil from aeriform products.

22. A process of refining mineral oils comprising bringing the oil into vapor phase, insuring the presence of air in said vapors, contacting the commingled vapors and air with a maintained water solution of heavy metal salt other than an iodide, and condensing and separating the treated mineral oil from aeriform products.

ARTHUR LACHMAN. 10
